SLIDING DOOR SUPPORTING APPARATUS

Ira Shafer, San Diego, Calif.

Application July 6, 1942, Serial No. 449,859

6 Claims.

(Cl. 20—19)

My invention relates to a sliding door supporting apparatus particularly arranged for use in suspending doors in shiftable edgewise relation with the door opening and shiftable into narrow walls, and the objects of my invention are:

First, to provide a sliding door supporting apparatus of this class in which the door rides freely on a carriage mounted on a track overhead and extending into the wall and in which the carriage will not jam or become wedged in the door supporting frame;

Second, to provide a door supporting apparatus of this class in which the door may be readily and quickly positioned or removed through the ordinary door opening from either side of the wall;

Third, to provide a sliding door supporting apparatus of this class in which the height of the door relative to its supporting track may be readily adjusted;

Fourth, to provide a sliding door supporting apparatus of this class in which the door may be installed by positioning one of the carriages first in the door opening near one side, while the other portion of the door remains in the room, then by shifting the other side of the door into position and mounting the same on the track;

Fifth, to provide a sliding door supporting apparatus of this class in which the door and the supporting apparatus may be readily installed or removed and adjusted to varying heights;

Sixth, to provide a sliding door supporting apparatus of this class in which the door supporting carriages may be quickly replaced when desired; and

Seventh, to provide a sliding door supporting apparatus of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a transverse sectional view of the door supporting track, carriage and door shown fragmentarily taken from the line 1—1 of Fig. 2; Fig. 2 is a fragmentary longitudinal sectional view taken from the line 2—2 of Fig. 1; Fig. 3 is a transverse sectional view of the track carriage and fragmentary portion of the door taken from

the line 3—3 of Fig. 4; Fig. 4 is a fragmentary longitudinal sectional view taken from the line 4—4 of Fig. 3 showing some of the parts in elevation to facilitate the illustration; Fig. 5 is a top or plan view on a reduced scale showing the door partially installed and in the process of installation with one side out in the room.

Similar characters of reference refer to similar parts and portions throughout the several views of the drawing:

The track members 1 and 2, door 3, carriage guides 4, carriage axle 5, carriage wheels 6, grease retainers 7, door supporting bolts 8 and 9, door supporting plate 10 and door supporting latch 11 constitute the principal parts and portions of my sliding door supporting apparatus.

The track members 1 and 2 are preferably L-shaped members, preferably made of wood and supported in spaced relation to each other, as shown best in Figs. 1 and 3 of the drawing and extend over the opening for the door and into the wall at the side of the door and form a track-way for supporting the door when it is shifted into the wall from the opening, as well as when the door closes the opening. These tracks may be supported in any manner desired and may be provided with special track portions 1a and 2a to provide a special wearing surface for the wheels 6.

Mounted on these tracks 1a and 2a or upon the inwardly extending portions of the members 1 and 2 is a pair of carriages each consisting of wheels 6, which are revolubly mounted upon axles 5 at their opposite ends. These wheels 6 are provided on their inner sides with grease retaining members 7 which are filled with relatively hard grease to provide lubrication for the carriage wheels on the axles.

Mounted on each of the axles 5 is a substantially U-shaped guide member 4 which extends downwardly between the inwardly extending portions of the track members 1 and 2, as shown best in Figs. 1 and 3 of the drawing. These members 4 serve as guides for guiding the wheels 6 in their proper relation on the track members 1 and 2 so that they do not bind or wedge in the open space between the track members.

Screw-threaded in one of the carriage guides 4 at its lower side and extending between the upwardly extending members thereof is a bolt 8 which is provided with a square shank portion 8a in its head which is positioned in a conforming shaped opening 8b and it is provided with a flat head portion 8c which fits against the top of the door and this bolt is secured in position by means of a plate 8d which is secured on the upper edge

of the door near one side by means of screws or the like.

Mounted in the carriage guide 4 on the other carriage is another bolt 9 which is screw threaded therein in the same way as the bolt 8, but this bolt 9 supports the door in a different manner. The door at this other side is provided with a rectangular shaped recess 3a, as shown best in Figs. 3 and 4 of the drawing, and over this recess is mounted a plate 10 by means of screws 10a. This plate is provided with an opening 10b therein and is provided with an enlarged portion 10c which is adapted to receive the head 9a of the bolt 9 and when the carriage together with the bolt 9 is shifted longitudinally with the upper side of the door, the square portion 9b of the bolt 9 will extend into the narrow portion of the slot 10b which prevents the turning of the bolt 9. This plate 10 is also provided with an upwardly extending pin 10d which extends upwardly a slight distance from the upper surface of the plate 10. It is also provided with a slot 10e in its end.

Positioned on the bolt 9 above the square portion 9b is a latch 11 which is an elongated plate provided with elongated slots 11a and 11b near its opposite ends and is adapted to fit over the bolt 9 above the square portion 9b at its one end and over the pin 10d at its opposite end when the door is installed in its operative position, shown in Figs. 3 and 4 of the drawing.

The ends of the inner extending portions of the track members 1 and 2 are cutaway at 1b and 2b a sufficient distance to permit the wheels of the carriage 6 to be raised upwardly through the opening provided by the cutaway portions 1b and 2b, as shown best in Fig. 5 of the drawing.

The operation and installation of my sliding door supporting apparatus is substantially as follows:

One of the carriage members is pivotally connected with the door at the one end in its adjusted relation, and positioned with the wheels traversing the door at one side of its upper edge and the lower side of the door is positioned slightly on an angle so that the carriage may be inserted through the openings formed by the cutaway portions 1b and 2b in Fig. 5 of the drawing, then the door is straightened up and the carriage enters the opening until the wheels are above the track portion, then the carriage, together with that particular side of the door is shifted longitudinally on the trackway, as shown in Fig. 5 of the drawing. Then the carriage with the bolt 9 and latch 11 is inserted through the opening formed by the cutaway portions 1b and 2b and the wheels shifted longitudinally onto the trackways of the members 1 and 2, the latch member extending backwardly. Then the door is shifted into alignment with the trackway and the free side of the door is shifted upwardly so that the bolt head 9a passes through the opening 10c, then by shifting the latch member 11 endwise, the square portion 9b of the bolt enters the narrow portion 10c of the slot so that the door is supported by the bolt head. The latch is then shifted to a position where the pin 10d enters the slot 11a of the latch member 11 and the door is ready for continuous operation.

To remove the door, a pencil or sharp pointed instrument is inserted through the slot 10e under the latch 11 and the latch raised until the point 10d is disengaged from the slot 11a. The latch is then drawn backwardly or the door moved away from the same until the bolt head reaches the opening 10c in the member 10 and the door

can drop below the bolt head and the door can then be shifted to the position shown in Fig. 5 of the drawing. Then the other carriage may be shifted backwardly and removed through the opening formed by the cutaway portions 1b and 2b.

It will be noted that with this structure and mode of operation no stops are required at the opposite sides of the door at the top side and the door may be adjusted at the one end by simply dropping the door at the one end and screwing the bolt 9 into the guide member 4.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an apparatus of the class described, the combination of a pair of enclosed spaced trackways, a pair of roller carriages arranged to ride on said trackways each provided with downwardly extending relatively wide guide means arranged to extend in the space between said trackways for guiding said roller carriages, and a door pivotally and adjustably connected with one of said carriages and latch means for connecting and disconnecting the other side of said door with the other carriage, said trackways provided with cutaway portions at one end which permits the insertion of said carriages from the lower side between said trackways.

2. In an apparatus of the class described, the combination of a pair of enclosed spaced trackways, a pair of roller carriages arranged to ride on said trackways each provided with downwardly extending relatively wide guide means arranged to extend in the space between said trackways for guiding said roller carriages, a door pivotally and adjustably connected with one of said carriages and latch means for connecting and disconnecting the other side of said door with the other carriage, said trackways provided with cutaway portions at one end which permits the insertion of said carriages from the lower side between said trackways.

3. In an apparatus of the class described, the combination of a pair of enclosed spaced trackways, a pair of roller carriages arranged to ride on said trackways each provided with downwardly extending relatively wide guide means arranged to extend in the space between said trackways for guiding said roller carriages, a door pivotally and adjustably connected with one of said carriages and latch means for connecting and disconnecting the other side of said door with the other carriage, said trackways provided with cutaway portions at one end which permits the insertion of said carriages from the lower side between said trackways, said latch means including a latch member shiftably connected with one of said carriages, plate means in connection with said door which receives a portion of said carriage and when shifted by said latch means secure said carriage in connection with said door.

4. In a sliding door apparatus of the class described, the combination with an overhead track positioned over the doorway and extending past the same, said track terminating a slight distance from one side of the door opening, of a door with rollers adjustably and pivotally connected to one upper corner of said door and extending above the same, a latch means secured to the opposite upper corner of said door including a plate rigidly secured to said door provided with a slot therein with an enlarged open portion at one end of said slot and a roller arranged to roll on said trackway and pass through the opening at the ends of said trackway over said doorway provided with a latch member which fits in the enlarged portion at the end of said slot and shiftable into said slot.

5. In a sliding door apparatus of the class described, the combination with an overhead track

positioned over the doorway and extending past the same, said track terminating a slight distance from one side of the door opening, of a door with rollers adjustably and pivotally connected to one upper corner of said door and extending above the same, a latch means secured to the opposite upper corner of said door including a plate rigidly secured to said door provided with a slot therein with an enlarged open portion at one end of said slot, a roller arranged to roll on said trackway and pass through the opening at the ends of said trackway over said doorway provided with a latch member which fits in the enlarged portion at the end of said slot and shiftable into said slot, and means in connection with said plate rigidly secured to said door which shifts the latch connected with said roller whereby said roller may be released from said door.

5. In a sliding door apparatus of the class described, a hanger including a pair of spaced rollers, a U-shaped guide member suspended from said rollers, a bolt adjustably mounted in the lower side of said U-shaped guide member and extending below the same provided with a head on its lower end and a door provided with a re-

cess in its upper side near one edge, a plate secured over said recess provided with a slot therein with an enlarged open portion at one end which receives the head of said bolt and with a narrow portion which locks the head of said bolt in said recess when the bolt is shifted relatively to the door.

6. In a sliding door apparatus of the class described, a hanger including a pair of spaced rollers, 10 a U-shaped guide member suspended from said rollers, a bolt adjustably mounted in the lower side of said U-shaped guide member and extending below the same provided with a head on its lower end and a door provided with a recess in its upper side near one edge, a plate secured over said recess provided with a slot therein with an enlarged open portion at one end which receives the head of said bolt and with a narrow portion which locks the head of said bolt 15 in said recess when the bolt is shifted relatively to the door, and means in connection with said plate rigidly secured to said door which shifts the latch connection with the roller whereby the roller may be released from the door.
